Ford Motor Company, Dearborn, Mich., a corporation
of Delaware

Application August 7, 1958, Serial No. 52,106

Term of patent 7 years

(Cl. D14—6)

Fig. 1 is a side elevational view of an automobile panel trim unit, showing my new design in use. The rear side portion of an automobile shown in broken lines is for the purpose of illustration only;

Fig. 2 is a side elevational view of the automobile panel trim unit;

Fig. 3 is a top plan view;

Fig. 4 is an enlarged sectional view taken substantially through the line 4—4 of Fig. 2 looking in the direction of the arrows;

Fig. 5 is a fragmentary sectional view taken substantially through the line 5—5 of Fig. 2 looking in the direction of the arrows;

Fig. 6 is a sectional view taken substantially through the line 6—6 of Fig. 2 looking in the direction of the arrows;

Fig. 7 is a sectional view taken substantially through

the line 7—7 of Fig. 2 looking in the direction of the arrows;

Fig. 8 is a sectional view taken substantially through the line 8—8 of Fig. 2 looking in the direction of the arrows;

Fig. 9 is a sectional view taken substantially through the line 9—9 of Fig. 2 looking in the direction of the arrows.

I claim:

The ornamental design for an automobile panel trim unit, substantially as shown and described.
